FLEXIBLE DISPENSER FOR CREAM DEODORANTS OR THE LIKE

Eldred G. Lustman, Mount Prospect, Albert Safianoff, Chicago, and Martin N. Sandler, Glencoe, Ill., assignors to The Gillette Company, Boston, Mass., a corporation of Delaware

Application June 19, 1959, Serial No. 56,428

Term of patent 14 years

(Cl. D58—6)

Fig. 1.

Fig. 2.

Fig. 3.

Fig. 1 is a view in front elevation of a flexible dispenser for cream deodorants or the like embodying our new design;

Fig. 2 is a view in side elevation; and

Fig. 3 is a plan view.

The dominant features of our design reside in the portions shown in full lines.

We claim:

The ornamental design for a flexible dispenser for cream deodorants or the like, as shown and described.
